UNITED STATES PATENT OFFICE.

GEORGE F. BUTTERFIELD, OF STONEHAM, MASSACHUSETTS.

MOLD FOR VULCANIZING RUBBER TO LEATHER.

SPECIFICATION forming part of Letters Patent No. 349,690, dated September 28, 1886.

Application filed December 21, 1885. Serial No. 186,313. (No model.)

To all whom it may concern:

Be it known that I, GEORGE F. BUTTERFIELD, of Stoneham, in the county of Middlesex and State of Massachusetts, have invented 5 certain new and useful Improvements in Molds for Vulcanizing Rubber to Leather, of which the following, taken in connection with the accompanying drawings, is a specification.

This invention relates to molds for vulcanizing rubber upon leather surfaces, and in its present application is especially designed to hold a shoe or boot in position and a quantity of rubber compound in a sole-shaped recess in contact with the leather sole, so that the rubber 15 may be vulcanized directly thereon, as stated in my application No. 173,972, filed August 10, 1885.

My improved mold is peculiar, in that one of its members has a suitably-shaped recess in 20 its outer face and an inclosed steam-chamber adjacent to such recess, while a cavity is formed in the other portion of the mold or between the two parts of which such portion is composed to receive the shoe or other article and hold it firmly in position with its sole directly 25 in contact with the portion of rubber compound contained in said recess. Steam inlet and exhaust pipes are provided for admission and escape of steam, and provision is made 30 for a water-current through the chamber when desired. The cap may be made of or lined with comparatively non-conducting material, so that the upper leather shall not be overheated.

35 In the drawings, Figure 1 is a vertical section on line xx , Fig. 2, through one of my improved molds containing a shoe; and Fig. 2 is a top plan of the lower section of the mold, showing the sole-shaped recess and the guide 40 pins or bolts. Fig. 3 is a transverse section on line yy , Fig. 1, but showing the mold with a pulp-lined cap.

A is the body of the mold, having the steam-chamber B within it, and provided with the 45 steam-inlet pipe C and exhaust-pipe D, in order to insure suitable pressure and current of steam. These pipes are furnished with suitable valves, E, to regulate or cut off the steam-current. The pipes may have branches, 50 as F, fitted with stop-cocks G, through which

a current of cold water may be passed through the chamber B, when desired, to condense the steam in the chamber and to cool the mold.

In the upper surface of the body A of the mold is a recess, R, shaped to correspond with 55 the form desired in the completed sole or other article being formed. The drawings show in Fig. 2 a sole-shaped recess, and in Fig. 1 a shoe is represented covering such recess, and a body of rubber filling the same and forming 60 the rubber sole S in immediate contact with the leather sole T of the shoe, to which it is permanently secured by vulcanization.

A further peculiarity of the mold is the cavity in its upper portion or cap V, to receive 65 the body of the shoe. This cavity may be open at the top to allow the shoe U to protrude, as shown, and will ordinarily constitute the space between the two parts of the cap, which are preferably made to separate laterally 70 at a central longitudinal line, as indicated in Fig. 1, where one half of the cap is removed. I provide guide pins or bolts W, and nuts or equivalent fastenings to secure the parts of the cap to each other and the cap to the body 75 A, so as to resist the strain due to the expansion of the rubber in vulcanizing.

The cap and the mold-body may be held in close contact by use of a press or any suitable 80 clamping devices.

Another feature of my invention, illustrated in Fig. 3, is designed to obviate overheating of the upper leather of the shoe, to secure 85 cheapness of construction of the cap, and a better fit between the edges of the shoe and the cap. This feature consists in making the mold-cap, or the part of it which comes in contact with the upper leather, of non-conducting material and of a material such as paper-pulp P or a compound thereof, which may be 90 applied in a plastic state over a shoe held in the mold and hardened under pressure, so as to conform internally to the exterior of the shoe near its sole edges.

The mold-cap may be a metallic shell with 95 a pulp lining molded within it the converse in shape of the shoe to be treated, so as to secure the strength of the shell and the fit and non-conducting quality of the lining. I do not limit myself to this form of cap, since I am 100

accustomed to make them also, as in Fig. 1, of cast metal, formed by first molding a plaster pattern from the shoe direct the reverse of the shoe and then casting the cap in the sand 5 molded as usual from this pattern.

I am aware that in the manufacture of rubber boots, &c., molds have been used having steam chambers or jackets surrounding the sole, the upper, and the leg of the boot, so as 10 to inclose the entire boot within the steam-spaces. Such apparatus would not be suitable for my purpose, since I apply the steam-heat only to the rubber sole and use the mold-cap 15 simply as a clamp to hold the shoe in proper relation to the recess containing the rubber sole, so that the rubber, by the heat and pressure, shall become cured and permanently affixed to the leather. I keep the cap or clamp 20 as cool as possible, to avoid injury to the leather. The recess R is sunken in the surface of my mold-body A, and not only shapes the bottom but also the edges of the rubber sole.

I claim as my invention—

1. The described mold for vulcanizing rub-

ber to leather, consisting of the hollow body 25 or steam-chamber A B, provided with suitable connecting pipes for the passage of steam and water, and having a sunken recess, R, formed in its surface to confine the rubber during vulcanization, in combination with the cap V 30 and with guide pins or bolts W, and nuts, serving as clamps, to hold the shoe to the mold-body A, with its sole T covering said recess R, substantially as set forth.

2. The hollow mold-body A, provided with 35 steam-connections, as described, and having the surface recess R, in combination with the recessed cap V, having an inner surface of non-conducting material, substantially as and for the purpose set forth.

In testimony whereof I have signed my name to this specification, in the presence of two subscribing witnesses, on this 26th day of October, A. D. 1885.

GEORGE F. BUTTERFIELD.
